US0D1051666S

(12) **United States Design Patent** (10) Patent No.: **US D1,051,666 S**
(45) Date of Patent: ** Nov. 19, 2024

(54) **SCREW FOR JUICE EXTRACTOR**

(71) Applicant: **NUC ELECTRONICS CO., LTD.**,
Daegu (KR)

(72) Inventor: **JongBoo Kim**, Daegu (KR)

(73) Assignee: **NUC ELECTRONICS CO., LTD.**,
Daegu (KR)

(**) Term: **15 Years**

(21) Appl. No.: **35/517,839**

(22) Filed: **Jul. 21, 2022**

(80) **Hague Agreement Data**

Int. Filing Date: **Jul. 21, 2022**

Int. Reg. No.: **DM/222914**

Int. Reg. Date: **Jul. 21, 2022**

Int. Reg. Pub. Date: **Jul. 21, 2023**

(30) **Foreign Application Priority Data**

Jul. 20, 2022 (KR) 30-2022-0029155

(51) **LOC (14) Cl.** **31-00**

(52) **U.S. Cl.**

(57)

CLAIM

The ornamental design for a screw for juice extractor as shown and described.

DESCRIPTION

1.1 : Perspective

1.2 : Front

1.3 : Back

1.4 : Left

1.5 : Right

1.6 : Top

1.7 : Bottom

The broken lines showing portions of the screw for juice extractor form no part of the claimed design.

1 Claim, 7 Drawing Sheets
